PLOW OR THE LIKE AND METHOD OF
MAKING SAMEReuel H. Figard, Detroit, Mich., assignor to Harry
Ferguson, Inc., Dearborn, Mich., a corporation
of DelawareNo Drawing. Application January 20, 1945,
Serial No. 573,815

2 Claims. (Cl. 51—282)

1

The invention relates to plows or like implements held in fixed or non-rotatable positions while in use and to a method of making them and more particularly to earth working implements having a new and improved earth engaging surface produced thereon by a novel method.

In such implements as plows one serious difficulty in the production thereof is in the development of a finished ground engaging surface that will scour. A plow, for example, is given as close to a proper shape as can be designed to meet a known soil condition and the curved turning surface is then ground and highly polished by a relatively costly process to obtain a smooth surface. Even so, the plows do not always scour satisfactorily. It is believed that this failure of the tools is due in part at least to the small lines and other irregularities produced in the surface by the grinding wheel.

An object of the invention is to provide a plow or like earth working implement which has a smooth earth working surface of proper form and curvature covered with extremely small projections capable when the tool is first drawn through the earth of being, in effect, burnished thereby to smoothness along lines extending in the direction of earth movement past such surface during use.

Another object is to provide a novel process of producing plows or the like which involves the steps in the finishing of the earth working surface of providing on said surface a dull, smooth finish comprised of minute projections, and finally polishing the surface by the relative movement of the surface and an abrading medium along the lines of movement of the earth past the surface in normal operation of the implement.

The invention may be employed advantageously in connection with any earth working implement having an earth working surface and it is particularly well adapted for such implements as plows, listers, middlebusters and the like in which the earth working surfaces must scour. This term, of course, refers to the movement of the earth across a surface freely, cleanly and without tending to adhere thereto.

Heretofore the final finish on the earth working surface of an implement of this character has been produced by one or more grinding operations. Such operations inevitably leave wheel or abrasive marks in the finished surface extending somewhat haphazardly in all directions. Such marks would of course interfere with the desired free earth movement across the surface.

2

According to the present invention I overcome this difficulty by providing on the earth working surface of a plow or the like, which has previously been fabricated in any suitable manner to bring the surface to its proper form and shape, a smooth dull finish which is free of grinding wheel marks and is comprised of extremely minute projections which cover the surface and produce its dull appearance. Such a surface is capable of being finished by the abrading, polishing action of the earth moving across it, the dull surface being, in effect, burnished to a smooth, good scouring condition.

The dull smooth finish may be produced on the surface quickly and effectively by forcing small particles of an abrasive agent against the surface. A wet blast method of surface treatment has been found to be quite effective in producing a surface which is smooth, in which the minute projections from the surface are quite uniform and in which surface scratches or wheel marks are substantially absent. Such a method involves the discharge of a high velocity stream of an oil or fluid borne abradant. The quantity of abradant used and its fineness determines the nature of the finish on the surface. Preferably a powdered abradant, such as that known commercially as "Novaclite," is employed in an oil carrier which inhibits oxidation of the finished surface.

The final step of finishing the surface of the implement to a condition in which it will scour effectively, involves the treatment of the surface by causing an abrading or polishing medium to move across the surface along lines which extend in the direction in which the earth will move past the surface during normal use. This may be done during the manufacture of the implement, but may be most efficiently and effectively performed by the action of the earth on the surface during the initial stages of the actual operation of the implement in the ground. The abrading, burnishing effect of the earth moving relatively to the particle covered surface will polish the surface. Since the direction of relative movement of the earth and the surface is the result of the use of the implement in normal operation, any surface scratches, marks or lines that may be formed in the implement surface will parallel the line of earth flow and hence cannot interrupt the clean free movement of the earth across the surface.

An earth working implement finished in this manner will have high scouring characteristics

after the implement has been used a relatively short time.

What I claim is:

1. The method of manufacturing a plow which includes the steps of forming the earth-engaging surface of a curvature suitable for turning a particular kind of earth, treating the surface by a blast of abrasive particles to eliminate scratches or wheel marks and to produce a uniform surface of dull appearance comprised of extremely minute projections, and then polishing said surface by causing a polishing agent to move across the surface along lines which extend in the same direction that the earth will move past the surface during normal use, thereby producing a surface which scours cleanly without the necessity of breaking in.

2. The method of treating a plow which includes the steps of forming the earth-engaging surface of a curvature suitable for turning a particular kind of earth, treating the surface by subjecting it to a high velocity stream of liquid carrying abrasive particles to eliminate scratches and wheel marks and to produce a uniform dull surface comprised of extremely minute projections, said liquid consisting of oil or the like pro-

tective material to form a residual protective film and thus prevent oxidation of the bare metal surface exposed by the action of the abrasive particles, and then polishing the unoxidized surface by causing a polishing medium to move across the surface along lines which extend in the direction in which the earth will move past the surface during normal use, thereby producing a surface in which any lines left by the polishing process are parallel to the line of earth flow and hence cannot interrupt the clean free movement of earth across the surface.
